(57) **CLAIM**

The ornamental design for a tower diffuser, as shown and described.

DESCRIPTION

FIG. 1 is a top perspective view of a tower diffuser; FIG. 2 is a bottom perspective view of FIG. 1; FIG. 3 is a front elevational view of FIG. 1; FIG. 4 is a rear elevational view of FIG. 1; FIG. 5 is a left side elevational view of FIG. 1; FIG. 6 is a right side elevational view of FIG. 1; FIG. 7 is a top plan view of FIG. 1; FIG. 8 is a bottom plan view of FIG. 1; and, FIG. 9 is an enlarged view of the portion indicated by line 9 in FIG. 1.

The dash-dash broken lines in the drawings illustrate the portions of the tower diffuser which form no part of the claimed design.

The dot-dash broken lines in the drawings are included for the purpose of illustrating the partial enlarged views.

1 Claim, 9 Drawing Sheets
